UNITED STATES PATENT OFFICE.

UBALD HEBERT, OF MANCHESTER, NEW HAMPSHIRE, ASSIGNOR, BY MESNE ASSIGNMENTS, TO DRAPER CORPORATION, OF HOPEDALE, MASSACHUSETTS, A CORPORATION OF MAINE.

AUTOMATIC FILLING-REPLENISHING LOOM.

1,218,258.

Specification of Letters Patent.

Patented Mar. 6, 1917.

Application filed July 3, 1916. Serial No. 107,248.

To all whom it may concern:

Be it known that I, UBALD HEBERT, a citizen of the United States, and resident of Manchester, county of Hillsborough, State 5 of New Hampshire, have invented an Improvement in Automatic Filling-Replenishing Looms, of which the following description, in connection with the accompanying drawing, is a specification, like characters 10 on the drawing representing like parts.

This invention relates to improvements in filling replenishing looms in which a supply of filling carriers is maintained in a hopper from which the filling carriers are transferred successively to the running shuttle by a suitable transerrer, and one object of 15 the invention is to provide means to secure the proper position of the filling carrier during transfer in order that it may be directed 20 into the shuttle in proper position.

The invention in its more specific form relates to a filling replenishing loom of the well known Northrop type in which an intermittently rotatable hopper is employed 25 carrying a series of filling carriers about its periphery.

More particularly the invention relates to filling replenishing looms making use of filling carriers having feeling slots in the barrel 30 thereof such as are illustrated for example in the patents to William Parker Straw No. 906,748 granted December 15, 1908, No. 1,053,673, granted February 18, 1913, and No. 1,092,959 granted April 14, 1914. When 35 this type of filling carrier is employed it is necessary that the slot therein shall be positioned in a definite relation to the feeler in order that the latter may work properly. Consequently the butts of the filling carriers 40 are provided with suitable positioning means, usually slabbed or flattened surfaces generally in planes at right angles to the longitudinal planes of the slot, and these surfaces are engaged by suitable jaws within 45 the shuttle to retain the filling carriers in position. The filling carriers are carried in the hopper and fed therefrom by the transerrer as upon the call for filling replenishment, but when a filling carrier is 50 forced from the hopper toward the shuttle it frequently rotates more or less and is not infrequently driven into the shuttle jaws in

improper position. As a result the feeler fails to operate or a smash is caused.

Heretofore it has been proposed as in the 55 patent to Alonzo E. Rhoades No. 1,167,363 granted January 4, 1916 to provide a vertically movable device which shall seize the positioning faces of the filling carrier and move down with the filling carrier maintaining it in position until it is forced into 60 the shuttle.

In my application 107,247 filed concurrently herewith I have disclosed an invention subordinate to that of my prior application 65 wherein as one of the chief features of the invention the guiding means is pivotally mounted and wherein also in the preferred form the guiding surfaces or elements are inclined to coöperate with inclined fill- 70 ing carrier seats in the hopper.

The present invention is in its main features subordinate to my prior application No. 76790, filed February 7, 1916, and in some respects subordinate to my aforesaid 75 application No. 107,247 filed concurrently herewith. In the present invention the guiding means moves rearwardly and forwardly in a rectilinear direction as in my first mentioned application and is provided 80 with inclined guiding surfaces as in my second aforesaid application. In this invention the guiding means instead of being moved rearwardly by a connection to the transerrer is moved rearwardly by the action 85 of the filling carrier as it is thrust by the transerrer from the hopper into the shuttle, the forward movement taking place under the action of a spring.

Other features of the invention will more 90 fully appear from the following description and the accompanying drawings and will be pointed out in the annexed claims.

In the drawings,

Figure 1 is an end elevation partly in 95 transverse section of a sufficient portion of a loom necessary to disclose one of the preferred embodiments of my invention.

Fig. 2 is a sectional view of the hopper stand showing in plan the guiding means 100 forming the subject matter of this invention.

The general construction of the loom may be and is that of the well known Northrop

type of filling replenishing loom and needs no extended description. It includes a rotatable battery feeder or hopper comprising parallel disks between which filling carriers such as bobbins are mounted in a circular series.

One of these disks 1 is illustrated herein as having a peripheral series 2 of bobbin seats provided with parallel walls 3 adapted to engage the slabbed positioning faces upon the butts of the bobbins. The hopper is rotatably mounted upon a shaft or stud 4 rigidly secured to a hopper stand 5 having a laterally extending bracket 6 by which it is secured to the loom frame. Said bracket has an extension 6^a to which is secured an abutment 7 having grooves adapted to engage the rings upon the bobbin and to direct the bobbin in its transfer from the hopper to the shuttle.

A circular flange 8 on the hopper stand surrounding the disk 1 serves to protect the butts of the bobbins until they reach substantially transfer position at which point 25 the flange is interrupted and a pivoted bobbin support 9 provided which holds yieldably the bobbin against the abutment 7 during its transfer.

The mechanism for effecting transfer is 30 of a well known type comprising a transfer arm 10 pivotally mounted upon a stud 11 extending from the hopper stand and provided with a downwardly extending arm 12 through which it is actuated upon a call 35 for filling replenishment. The opposite or free end of the transfer arm is provided with a curved head or hammer 13 adapted to engage the base of the bobbin and thrust it from the hopper into the shuttle. The 40 transerrer is normally retained in elevated position by a spring 14 anchored to the stud 11 and extending beneath the arm 10.

The hopper is rotated to bring the bobbins successively into a transferring position by means of a dog 15 pivotally mounted upon a stud on the transfer arm 10, the dog 15 having a tooth 16 in operative engagement with teeth 17 upon a circular ratchet secured to or integral with the disk 50 1. Reverse rotation of the hopper is prevented by a counterweighted pawl 18 adapted to engage the teeth 17 of the ratchet.

In the operation of the device the transfer arm 10 is forced downwardly by the 55 usual bunter mechanism on the lay causing the head 13 to strike the base of the bobbin and thrust it forcibly from the hopper into the shuttle. During the downward movement of the transfer arm the tooth 16 of the dog 15 falls beneath the next succeeding tooth upon the ratchet 17 and upon the elevation of the transfer arm 10 causes, through the ratchet 17, the rotation of the hopper one step to place the next bobbin in 60 65 transfer position.

By reason of the fact that the butt of the bobbin is held by the bobbin support 9 in rolling contact with the abutment 7 as transfer takes place the force applied by the transerrer to the butt of the bobbin has a 70 tendency to rotate it so that during its passage from the hopper to the shuttle it may become improperly positioned.

The present invention comprises the introduction between the hopper and shuttle 75 of a guide or conveyer normally held in communicative relation to the bobbin seat of the hopper which is in transferring position but adapted upon transfer to be moved rearwardly into registry with the shuttle 80 by the movement of the filling carrier under the influence of the thrust of the transerrer.

The bobbin 20, for the transfer of which the present invention is designed, is provided with a feeling slot in its barrel a short distance from its base. The butt of the bobbin is slabbed to form parallel positioning faces 22 adapted to be engaged by guides in the shuttle to retain the feeling 85 slot in proper position to receive the feeler upon substantial exhaustion of filling.

The walls of the peripheral bobbin seats in the hopper engage the positioning faces on the bobbins and retain them in substantially proper position for transfer to the shuttle. The bobbin seats preferably are inclined to the radii of the hopper so that when a bobbin reaches transferring position, the positioning faces of its butt are 90 slightly inclined to the vertical and any rotative movement of the bobbin caused by engagement with a guide in the shuttle will tend to position the bobbin in the shuttle 95 jaws.

The guiding means for retaining the rotative position of the bobbin unchanged as it is being transferred from the hopper to the shuttle comprises a conveyer or chute 100 23 having walls 24 adapted to form continuations of the walls of the bobbin seat which is in transferring position.

The conveyer has an extension 25 which is slidably mounted upon the extension 6^a of the bracket stand and is held down upon said extension by a plate 26 which may be secured to the bracket stand by the same rivets or bolts 27 which secure the abutment 7 thereto. The end of the conveyer extension 25 is flanged upwardly to form a seat for a helical spring 28 which rests its opposite end against a post 29 secured to or formed integral with the hopper stand bracket 6. It will be noted that the hopper construction and hopper bracket construction illustrated herein are substantially the same as those illustrated in my prior Patent No. 1,185,094 and that the only modification of the patented structure which is necessary to permit the embodiment of the improve- 105 110 115 120 125 130

ment herein is to cut away the portion of the lateral extension of the hopper stand bracket from the points *a* to *b* preferably leaving a supporting ledge *c* therebetween 5 for the extension 25 of the conveyer.

In the operation of the device the actuation of the transfer arm forces the bobbin from the hopper into the inclined guideway of the conveyer or chute 23. The force of 10 the transfer arm first causes a rotation of the hopper as the bobbin is maintained against the abutment 7 by the bobbin support 9. As the bobbin passes from the 15 hopper into the conveyer the latter is moved rearwardly against the action of the spring 28. This movement of the conveyer is in consonance with the movement of the lay as it approaches transferring position so that the action of the reciprocating conveyer 20 has the double function of maintaining the bobbin against rotative movement during transfer and also of providing a longer period in which the conveyer and shuttle are in registry or communication. This insures 25 the proper positioning of the slabbed positioning faces of the bobbin butts between the guiding means on the shuttle jaws.

It is to be understood that various modifications of construction may be made within 30 the scope of the invention defined by the following claims and also that while the guiding means interposed between the hopper and shuttle have been described with particular reference to the use of bobbins 35 having feeding slots in the barrels thereof it is adapted to be used with bobbins of the usual type for the purpose of more effectively insuring transfer.

Having thus described my invention what 40 I claim as new and desire to secure by Letters Patent is:

1. A filling replenishing loom comprising a hopper adapted to contain a plurality of filling carriers, a transerrer and means to 45 actuate the same to thrust a filling carrier into the shuttle, a slidably mounted conveyer intermediate of said hopper and shuttle provided with guiding instrumentalities adapted to engage and position the filling 50 carrier being transferred and so disposed as to cause said conveyer to be moved rearwardly into registry with the shuttle by the movement of the filling carrier under the influence of the thrust of the transerrer.

55 2. A filling replenishing loom comprising a rotatable hopper having a peripheral series of filling carrier seats inclined to the

radii of the hopper, a transerrer and means for actuating the same to thrust a filling carrier into the shuttle and a slidably 60 mounted conveyer intermediate of the hopper and shuttle having guiding instrumentalities adapted to receive a positioned filling carrier from the hopper and to maintain the filling carrier in the same rotative position during transfer, said conveyer being movable into registry with the shuttle by the movement of the filling carrier under the influence of the thrust of the transerrer. 65

3. A filling replenishing loom comprising 70 a rotary hopper having a peripheral series of filling carrier seats, a hopper stand having a supporting bracket, a transerrer and means for actuating the same to thrust a filling carrier from said hopper into the 75 shuttle, a conveyer intermediate of said hopper and shuttle slidably mounted upon said bracket and resilient means for normally maintaining said conveyer in communicative relation with a filling carrier 80 seat in said hopper, guiding instrumentalities upon said conveyer adapted to receive a positioned filling carrier from the hopper and direct the same to the shuttle, said guiding means being positioned to cause said 85 conveyer to be moved rearwardly into registry with the shuttle by the movement of the carrier under the influence of the thrust of the transerrer.

4. A filling replenishing loom comprising 90 a rotary hopper having a peripheral series of filling carrier seats inclined to the radii of said hopper, a hopper stand having a supporting bracket, an abutment for guiding the filling carrier from the hopper to 95 the shuttle supported by said bracket, a transerrer and means for actuating the same to thrust a filling carrier from said hopper into the shuttle, a conveyer intermediate of said hopper and shuttle, having 100 guiding walls forming extensions of the walls of said filling carrier seats, said conveyer being slidably mounted upon said bracket and resilient means for normally maintaining said conveyer in communicative relation with a filling carrier seat in 105 said hopper and adapted to permit said conveyer to be moved rearwardly into registry with the shuttle by the movement of the carrier under the influence of the thrust of 110 the transerrer.

In testimony whereof, I have signed my name to this specification.

UBALD HEBERT.
